UNITED STATES PATENT OFFICE.

CHARLES H. METZ, OF WALTHAM, MASSACHUSETTS.

DESIGN FOR A GEAR-CASE MEMBER.

SPECIFICATION forming part of Design No. 30,409, dated March 28, 1899.

Application filed March 2, 1899. Serial No. 707,557. Term of patent 7 years.

To all whom it may concern:

Be it known that I, CHARLES H. METZ, of Waltham, in the county of Middlesex and State of Massachusetts, have invented and produced a new and original Design for a Gear-Case Member, of which the following is a specification, reference being had to the accompanying drawings, forming part thereof.

In the drawings, Figure 1 represents a perspective view of a gear-case member, illustrating my new design. Fig. 2 represents a sectional view of the same, taken on a line $\alpha\alpha$, Fig. 1.

The leading feature of my new design for gear-case members consists in the design as herein shown and described.

As shown in the drawings, the circular rim 5 has the inwardly-extending flange 6, open at its center and at the side from which the smaller rim 7 extends. This smaller rim 7 extends approximately at right angles with the axis of the rim 5 and has the lip 8, which extends but partially around the inner circle of the rim 7 and connects at its ends with the flange 6.

What I claim is—

The design for a gear-case member as herein shown and described.

CHARLES H. METZ.
